UNITED STATES PATENT OFFICE.

ALFRED H. FRANCFORT, OF JERSEY CITY, NEW JERSEY, ASSIGNOR TO NIAGARA HYDRAULIC ENGINE CO., A CORPORATION OF PENNSYLVANIA.

AIR-FEED FOR HYDRAULIC RAMS.

No. 885,855.

Specification of Letters Patent.

Patented Nov. 13, 1906.

Application filed August 21, 1905. Serial No. 274,992.

To all whom it may concern:

Be it known that I, ALFRED H. FRANCFORT, a citizen of the United States, residing at Jersey City, in the county of Hudson and State of New Jersey, have invented a new and Improved Air-Feed for Hydraulic Rams, of which the following is a full, clear, and exact description.

My invention relates to hydraulic rams, 10 the same residing particularly in the means for feeding air to the air-chamber for maintaining a constant air cushion or pressure therein.

As is well known, in this class of devices 15 the pumping action of the water is effected against a cushion of air in an air-chamber, and unless air be constantly supplied to such chamber that which was originally contained therein will be absorbed by the water, and 20 the pumping action will then be effected against a solid unyielding body. Various expedients have been resorted to for feeding air to the air-chamber of a hydraulic ram, most of them depending for their action upon the reduction in the pressure after the blow has been 25 struck by the water, the said reduction in pressure serving to draw in through a suitable orifice a small quantity of air, which upon the next stroke is forced up into the air-chamber. It is necessary, however, that the 30 quantity of air thus admitted be very accurately regulated, and the size of the opening or orifice must necessarily be adjusted for every machine which is installed on account of the varying conditions under which 35 different machines are called upon to operate.

My invention is designed for the production of an air-feed for hydraulic rams in which the quantity of air admitted after each 40 stroke thereof may be controlled with absolute accuracy and without danger of clogging any of the ports or orifices. It is also designed for the purpose of providing such an air-feed in which danger of drawing the air-bubble back into the impetus-valve chamber 45 is reduced to a minimum and the danger of forcing the air-bubble out through the passage through which it entered is absolutely prevented.

50 The details of the invention will hereinafter appear, and that which I regard as new will be set forth in the claims.

In the drawings forming part of this specification, Figure 1 is a plan view of a hydraulic

ram embodying my improvements. Fig. 2 55 is a longitudinal section of the same. Fig. 3 is a transverse section on the line 3 3 of Fig. 2, and Fig. 4 is a similar view showing an old form of construction upon which my invention is an improvement. 6c

Like reference-numerals indicate like parts in the different views.

The casing of the hydraulic ram shown is provided with a valve-chamber 1 for the impetus-valve 2, a valve-chamber 3 for the 65 main valve 4, and a passage 5 between said valve-chambers. The air-chamber 6 is secured to said casing above the main valve 4 and has leading therefrom a delivery-pipe 7. The drive-pipe 8 enters the casing at a point 70 beneath the impetus - valve 2, as clearly shown.

All of these parts are old and well known, being substantially the same as the corresponding parts shown in the patent to 75 Smith, No. 748,113, dated December 29, 1903, and the operation thereof is well understood.

The air-inlet, through which air is admitted for maintaining the pressure within the chamber 6, is ordinarily located in the passage 5 between the valve-chambers 1 and 3. A common form of such device is illustrated in Fig. 4 of the drawings, in which, as will be seen, the upper wall of the rectangular passage 85 5 is provided with a tapering screw-threaded opening, into which a plug 9, having a correspondingly - shaped screw - threaded cone-shaped head, is adapted to fit. This plug has a port 10 therein, which extends upwardly from its central point and communicates with a transverse port 11. To regulate the admission of air with the plug 9, it is necessary to screw the same into the upper wall of the passage 5 to a greater or less extent, 95 and thus cut off by the wall of said passage a greater or less part of the port 11. It will be obvious, however, that if the plug 9 be screwed in to its greatest extent and the device is adapted to admit air a certain pre- 100 determined portion of the port 11 will be exposed. The size of the passage through the plug 9 therefore cannot be decreased, as said plug had been screwed in to the limit of its movement. If it be desired to increase 105 the size of the passage through said plug, it is necessary to unscrew the same partially from the opening in the wall of the passage 5;

but in this case the outer screw-threaded walls of said plug are removed from the walls of the opening in which it fits, and consequently a leak takes place around said plug. 5 The same is therefore very deficient in providing for the accurate regulation of the air-supply to the passage 5. Moreover, as this plug 9 is located in the top wall of the passage 5 there is always a tendency to force 10 back the bubble of air which enters through the ports 11 10 through the same passage. This defeats the very purpose of the air-feed. By my invention, which is most clearly 15 illustrated in Fig. 3 of the drawings, these objections are entirely overcome. I employ a plug 12, having a screw-threaded cone-shaped end which is adapted to fit a correspondingly-shaped screw-threaded opening in the side wall of the rectangular passage 5 between 20 the valve-chambers 1 and 3. This opening in said side wall is located a short distance beneath the top of said passage. The plug 12 is provided with a central aperture or port 13 at its inner end and with an enlarged screw-threaded axially-arranged opening 14 in line 25 with the port 13.

A shoulder 15 is formed at the meeting-point of the port 13 and opening 14, and a transverse port 16, intersecting the opening 30 14, is also provided in the plug 12.

Fitting within the opening 14 in said plug 35 is an adjusting-screw 17, having a head 18 thereon and provided with a jam-nut 19, by means of which it may be locked in adjusted 40 position. The inner end of the screw 17 is adapted to engage the shoulder 15 to cut off entirely the passage for air through the plug 12 and is adapted to be moved, as shown in Fig. 3 of the drawings, to a position opposite 45 the transverse port 16 for the purpose of regulating the size of the passage through said plug. The inner end of said screw is cut off square, so that an annular passage between it and the inner wall of the opening 14 is avoided, which would be produced when the ordinary form of needle-valve is employed. These annular passages are objectionable in that clogging is much more apt to occur when they are formed. The 50 plug 12 is somewhat elongated in order that it may project out to a point where ready access may be had thereto. It is also provided with a semicircular shield or guard 20, held in place by the jam-nut 19, the said 55 shield being provided for the purpose of cutting off the port 16 from the waste water escaping through the passage controlled by the valve 2. Without the provision of this shield there is danger of the passage through 60 the plug 12 being filled with water and that upon the reaction of the ram water will be sucked in through the port 13 instead of air.

Now it will be observed that all that is necessary to do in order to apply my device 65 is to screw the cone-shaped end of the plug

12 into the threaded opening in the side wall of the passage 5, and once in place it is never necessary to remove the same. It may be screwed up just as tight as may be desired, which cannot be done in the case of plug 9. 70 (Shown in Fig. 4.)

When a ram is first installed, it is necessary to cut off the supply of air altogether until sufficient pressure has been generated within the air-chamber 6. With my device 75 this may be done by simply screwing up the screw 17 until the inner end thereof comes into engagement with the shoulder 15. When sufficient time has elapsed for a body of water to have accumulated in the chamber 80 6 beneath the air at the upper part of said chamber, the screw 17 is moved outwardly until it assumes a position substantially as shown in Fig. 3 of the drawings, where the transverse port 16 is partially uncovered. 85 An opening is thus produced through which air may be admitted to the passage 5. The size of this opening, however, will necessarily vary with the conditions under which the ram is operated. Consequently the adjustment can never be finally made until after installation. When once made, it remains permanently. After adjustment of the screw 17, therefore the jam-nut 19 is turned and the screw locked in position. 90

The port 16 is cut off from the overflow-water from the valve 2, and upon "back-kick" or reaction of the ram when a reduction in the pressure within the passage 5 takes place a small quantity of air is drawn 100 in through the ports 16 and 13 in a well-known manner. This small quantity of air in the form of a bubble rises to the top of the passage 5 out of line with the inner end of the port 13, and consequently cannot upon the 105 next stroke of the ram be forced back through the ports 13 and 16. On the other hand, it is forced up through the valve-chamber 3 into the air-chamber 6 and serves to replenish such air in said chamber as may 110 be absorbed by the water therein. Said air-bubble is also prevented from being drawn back into the valve-chamber 1, from which it might be forced out through the opening controlled by the impetus-valve 2, by the 115 vertical wall 21, which supports the diaphragm 22.

Having now described my invention, what I claim is—

1. In a hydraulic ram, having the usual 120 impetus-valve, main valve and passage between the same, a plug secured to and extending through one of the side walls of said passage, the said plug having longitudinal and transverse ports, a regulating-screw for controlling the passage through said ports, a shield embracing said plug for cutting off said transverse ports from the waste water and a jam-nut on said screw for preventing the turning movement thereof, the said nut 130

acting upon said shield for holding the latter in place.

2. In a hydraulic ram, having an impetus-valve, a main valve and a passage connecting the same having a horizontal portion therein, an air-feed extending through the side wall of the horizontal portion of said passage at a point below the upper end thereof, and a wall in the horizontal portion of said passage

between said air-feed and the chamber of 10 said impetus-valve, as and for the purpose set forth.

In witness whereof I subscribe my signature in the presence of two witnesses.

ALFRED H. FRANCFORT.
